UNITED STATES PATENT OFFICE.

JOSEPH NEMEC, OF CHICAGO, ILLINOIS.

DOOR HOLDER.

Application filed November 15, 1923. Serial No. 274,805.

To all whom it may concern:

Be it known that I, JOSEPH NEMEC, a citizen of the United States, residing at Chicago, in the county of Cook and State of Illinois, have invented certain new and useful Improvements in a Door Holder, of which the following is a specification.

This invention relates to door holders and has for its object to provide means for use in conjunction with door checks or return members which will permit holding the door in any desired open, or partially open position, this being an improvement on the invention disclosed in my earlier Patent 15 1,241,478 patented September 25th, 1917. In the instant application I have disclosed a structure which may be readily applied to existing door checks which may be manually operated when the door is in the desired position to maintain it in such position and which is so constructed that a further slight opening movement of the door will move the holding device out of operative position and permit automatic closing 20 or further opening of the door.

Another object consists in the provision of means yieldably holding the engaging member in engaging position, which means is constructed to yieldably hold the engaging member out of engaging position. Another object consists in constructing the detent or holding mechanism in such wise that it may be readily reversed to accommodate the attachment of the door check to 30 differently mounted doors, or to doors swinging in either direction.

Still another object consists in the provision of operating means to a door, or the like, to actuate the holder at a point distant 40 from the door check.

These and other objects will be more fully explained and described in the following specification and shown in the accompanying drawing in which—

Figure 1 is a front elevation of a portion of a door showing a door check and mechanism embodying my invention applied thereto.

Fig. 2 is a plan view of the same drawn to a large scale showing the pawl in holding position.

Fig. 3 is a similar view showing the pawl in release position and yieldably held by the sear member.

Fig. 4 is an end elevation showing a por-

tion of the door check arm and ratchet broken away, for illustration.

Fig. 5 is a front elevation showing operating means for operating the door holder at a point distant from the door check. 60 10 indicates, generally, a door check of conventional construction as applied to a door, it being well known to those skilled in the art that these devices comprise, generally, a shaft 11 whose movement from normal position is restricted by a spring, fluid, or both, or other means; these means also acting to normally return the shaft to normal, or door closing position. An arm 12 is secured to the shaft to rotate therewith 65 and is pivotally attached at one extremity to a second arm 13 which is attached to the wall, jamb, or the like. It will be understood that these details are not an integral part of my invention and I do not wish to 70 be considered as restricted to any particular form or arrangement of them except as necessary to the proper functioning of the door holder mechanism.

I provide a cap or cover plate 14 at the 80 top of the door check which may be substituted for that ordinarily provided, or in the attachment of my invention to existing door checks, may be secured to the cover or casing.

This cap 14 is stationary and provided with a projecting portion 14^a. Rotatably mounted upon the cap 14, is a toothed ratchet 16 having the serrations or notches 16^a. A cap screw 17 is threaded into the 90 arm 12 and has a projecting tip 17^a engaging one of the notches 16^a, this construction permitting attachment of the arm 12 in any adjusted position to and with respect to the cap 14. Coactable with ratchet 16 is the 95 pawl 18 having the opposed engaging lugs 18^a provided with the angularly disposed stem 18^b extending through the pawl into the projecting portion 14^a of cap 14. At the lower extremity of the stem 18^b is the arm 100 19 by means of which the pawl 18 may be manually or mechanically moved to and from position wherein one of the lugs 18^a will engage a notch 16^a in the ratchet 16. The inner side of lug 18^a is curved at its 105 juncture with the main portion of the pawl 18 and this curvature and the off-set pivotal axis of the stem 18^b results in the movement of the pawl 18 out of position engaging the ratchet 16 when the latter is moved 110

in the direction of the arrow indicated in Fig. 2, for example, this being the direction of movement when door is opening.

I provide a sear member 20 having opposed notches 20^a near one extremity and provided with a pair of apertured lugs 20^b at the other extremity, through either one of which may be inserted a pivot screw 21 into the projecting portion 14^a of cap 14. When the pawl 18 is moved to release or non-engaging position as indicated in Fig. 3, a corner 18^c thereof will ride into the notch 20^a and be yieldably maintained in such position by the sear 20. A spring 25 is attached to the projecting end of the sear 20 at one end and at the other to a screw 26 projecting outwardly from the cap 14 or other suitable location. The free end of sear 20 is preferably downwardly bent as indicated at 20^e in Fig. 4, for example. The spring 25 maintains the sear in position pressing against the pawl 18 as will be obvious and thus insures retention of the pawl in release position by the notch 20^a, as shown in Fig. 3. The provision of a pair of notches 20^a and a pair of apertures 20^b permits reversal of the sear to accommodate reverse mounting of the door check. The pawl is likewise constructed for reversal, it being merely necessary to move plate 14 180° and rearrange the pawl and sear 20 for such reversal.

In the use of my device when the door has been swung to position in which it is desired to be maintained, the arm 19 may be moved inwardly to engage pawl 18 with ratchet 16, after which, upon release of the door, the return mechanism will force the ratchet against the pawl in engagement.

In order to actuate the holding mechanism when it is used with high doors, or where the door swings against a wall or the like, I may find it desirable to apply operating mechanism and I have illustrated such mechanism in Fig. 5. An arm 30 is provided pivoted at one extremity at 30^a to a projecting bracket 31 secured to and projecting from the cap 14. At its other extremity the arm 30 is apertured to permit the insertion of a sliding rod 32 upon one end of which I have assembled a threaded nut 32^a, a coil spring 33 extending between washer 34 and the nut 32^a at its lower end 30^b of arm 30. Intermediate these extensions the arm 30 is provided with a contacting lug 30^c arranged to contact with the arm 19. Rod 32 at its other extremity is pivoted at one extremity 34^a of bell crank 34, which at its central apex portion is pivoted at 34^b to the door. At the other extremity 34^c, the bell crank 34 is pivotally attached to operating rod 35 terminating in the engaging knob 36 which portion rides into the L shaped slot 37^a of plate 37 attached to the door, the lever mechanism composed of the rods 32,

35 and bell crank 34 being similar to that disclosed in my prior patent mentioned above. When the knob 36 is moved into the lower angularly disposed portion of slot 37^a the pawl 18 will be moved into engagement with the ratchet 16, the spring 33 providing a yielding element whereby if the pawl is not in alignment with a notch in the ratchet it may ride on the ratchet until a notch is aligned with it. This also permits for opening movement of the door against the action of spring 33, intentionally or accidentally.

It will be apparent that with the lever actuating mechanism just described out of operative position, a slight opening movement of the door will serve to disengage the pawl 18 and move the same to release position wherein it will be yieldably held by the sear 20. Only a slight pressure on the arm 19 is necessary to move the pawl from release position into engagement with the ratchet.

I do not wish to be restricted to the form of my invention disclosed and shown, save as I have defined it in the appended claims.

What I claim is:—

1. In combination, a door check comprising a rotatable arm operatively attachable to a door, a ratchet rotatable with said arm, a pawl having a portion engageable with said ratchet, and means operable to move said pawl into and out of engagement, said pawl being constructed and arranged to move out of engagement with said ratchet upon movement of the latter in one direction.

2. In combination, a door check comprising a main rotatable shaft, a ratchet concentric therewith, an arm attached to said shaft, a ratchet, a pawl having a portion engageable with said ratchet, means operable to move said pawl into and out of engagement with said ratchet, and means to yieldably hold said pawl out of engagement with said ratchet.

3. In combination, a door check comprising a main rotatable shaft, a ratchet concentric therewith, an arm attached to said shaft, a ratchet, a pawl having a portion engageable with said ratchet, means operable to move said pawl into and out of engagement with said ratchet, and means to yieldably hold said pawl either in or out of engagement with said ratchet.

4. In combination, a door check comprising a rotatable arm operatively attachable to a door, a ratchet rotatable with said arm, a pawl having a portion engageable with said ratchet, means operable to move said pawl into and out of engagement with said ratchet and means to hold said pawl out of engagement with said ratchet, said last named means comprising a pivot sear member.

5. In combination, a door check comprising a rotatable arm operatively attachable to a door, a ratchet rotatable with said arm, a pawl having a portion engageable with 5 said ratchet, means operable to move said pawl into and out of engagement with said ratchet, means to hold said pawl out of engagement with said ratchet, said last named 10 means comprising a pivot sear member, and means maintaining said sear in yielding contact with said pawl.

6. In combination, a door check comprising a rotatable arm operatively attachable to a door, a ratchet rotatable with said arm, 15 a pawl having a portion engageable with said ratchet, means operable to move said pawl into and out of engagement with said ratchet and means to hold said pawl out of engagement with said ratchet, said last 20 named means comprising a pivot sear member, said sear being provided with a notch engageable with a portion of said pawl when the latter is in release position with respect to said ratchet.

25 7. In combination, a door check comprising a rotatable arm operatively attachable to a door, a ratchet rotatable with said arm, a pawl movable into and out of engagement with said ratchet, said pawl being provided with a manually actuatable arm.

30 8. In combination, a door check having a cap, a rotatable arm, a ratchet rotatable with said arm, a pawl pivotally mounted on said cap and movable into and out of engagement with said ratchet.

35 9. In combination, a door check having a cap, a rotatable arm, a ratchet rotatable with said arm, a pawl pivotally mounted on said cap and movable into and out of engagement with said ratchet, a sear member pivoted upon said cap and constructed and 40 arranged to yieldably maintain said pawl in non-engaging position with respect to said ratchet.

45 10. In combination, a door check having a cap, a rotatable arm, a ratchet rotatable with said arm, a pawl pivotally mounted on said cap and movable into and out of engagement with said ratchet, a sear member 50 pivoted upon said cap and constructed and arranged to attachably maintain said pawl

in non-engaging position with respect to said ratchet, a spring maintaining said sear in yielding contact with said pawl.

11. In combination, a door check having 55 a cap, a rotatable arm, a ratchet rotatable with said arm, a pawl pivotally mounted on said cap and movable into and out of engagement with said ratchet, a sear member 60 pivoted upon said cap and constructed and arranged to attachably maintain said pawl in non-engaging position with respect to said ratchet, a manually actuatable arm associated with said pawl for movement of the latter to and from engaging position. 65

12. In combination, a door check having a cap, a rotatable arm, a ratchet rotatable with said arm, a pawl pivotally mounted on said cap and movable into and out of engagement with said ratchet, a sear member 70 pivoted upon said cap and constructed and arranged to yieldably maintain said pawl in non-engaging position with respect to said ratchet, said sear and pawl being reversible to permit coaction with the door 75 check on doors swinging in either direction.

13. A door check having a cap, an arm, a ratchet rotatable therewith, a pawl pivotally mounted on said cap to engage said 80 ratchet, said pawl being movable into and out of engagement with said ratchet.

14. A door check having a cap, an arm, a ratchet rotatable therewith, a pawl pivotally mounted on said cap to engage said 85 ratchet, said pawl being movable into and out of engagement with said ratchet, and means to yieldably hold said pawl out of engagement with said ratchet.

15. A door check having a cap, an arm, 90 a ratchet rotatable therewith, a pawl pivotally mounted on said cap to engage said ratchet, said pawl being movable into and out of engagement with said ratchet, and means to yieldably hold said pawl out of 95 engagement with said ratchet, said pawl being provided with an operable arm attached thereto.

In testimony whereof, I have subscribed my name.

JOSEPH NEMEC.
